TWO-PIECE TELEVISION PICTURE TUBE

Rollie Hazel Sessions, Port Wentworth, Ga.

Application June 4, 1953, Serial No. 359,615

3 Claims. (Cl. 313—2)

This invention relates to the large picture tube of a television receiver, and in particular the plural type of cathode ray tube wherein the picture tube is formed of a plurality of sections with the sections positioned whereby a fluorescent layer in the section in which the electron gun is positioned transmits light to a photosensitive layer in the large tube.

The purpose of this invention is to reduce the replacement cost of television tubes as the part that requires replacement is the neck or electron gun and with this provided as a separate and independent unit it may be removed and replaced without replacing the large screen section of the tube.

Failure of a television tube is due to burning out of the electron gun in the neck portion of the tube and with the parts formed in one piece it is necessary to replace the entire tube including the gun and screen should the gun burn out. Both sections are comparatively costly and with one section being replaceable without the other, the cost of repairing a television set is greatly reduced.

With this thought in mind, this invention contemplates means for forming a television receiver tube in two sections whereby each section is sealed and wherein both the screen section and electron gun section are replaceable independently.

The object of this invention is, therefore, to provide means for forming the large tube of a television receiver whereby the electron gun section is adapted to be separated from the large end or screen section and wherein the two parts may be assembled without disturbing the large or screen section.

Another object of the invention is to provide a two piece television picture tube in which both the screen section and electron gun section are removable and replaceable independently and in which the tube is adapted to replace conventional television tubes in cabinets now in use.

A further object of the invention is to provide a two piece television picture tube in which both parts are removable and replaceable and in which the tube is of a simple and economical construction.

With these and other objects and advantages in view the invention embodies a plural type of cathode ray tube in which a fluorescent layer in a section in which the electron gun is positioned transmits light to a photosensitive layer in another section and in which the bell shaped section is provided with a cylindrical flange adapted to receive one end of the neck and in which fastening elements are extended across the ends of the neck and bell shaped section for retaining the parts in assembled relation.

Other features and advantages of the invention will appear from the following description taken in connection with the drawing, wherein:

Figure 1 is a side elevational view of the two piece television picture tube with parts broken away and parts in section illustrating fastening elements for connecting the neck to the screen section.

2

Figure 2 is a detail showing a longitudinal section through the connection between the two sections of the tube with the parts shown on an enlarged scale and illustrating a modification wherein the parts are secured together with bolts.

Figure 3 is a side elevational view of the joint connecting the neck to the screen section with the parts as shown in Figure 1.

Figure 4 is a detail illustrating rings positioned around 10 collars on the two sections of the tube, the rings providing means for connecting fastening elements across the adjoining ends of the tube sections.

Referring now to the drawing, wherein like reference characters denote corresponding parts the improved two 15 piece television picture tube of this invention includes a neck 10, a bell shaped screen section 11, a collar 12 extended around and spaced from one end of the neck 10, a collar 13 positioned around and extended from a cylindrical section 14 of the section 11, rings formed with 20 sections 15 and 16 positioned against surfaces of the collars and fastening elements, such as the springs 17 connecting the rings.

With the parts formed as illustrated in Figure 1 the 25 neck or electron gun section 10 is sealed and one end of the neck is provided with a fluorescent layer which transmits light to the photosensitive layer 19 in the end of a cylindrical section 20 of the bell shaped section 11.

The end of the neck 10 is designed to nest in the 30 cylindrical section 14 of the bell shaped section 11 of the tube and with a gasket 21 positioned between the lenses of the two sections the lenses will be spaced apart, as shown in Figure 1.

As illustrated in Figure 4 the rings formed with the 35 sections 15 and 16 are provided with ears 22 on the sections 15 and 23 on the section 16 and these ears are provided with openings 24 and 25, respectively, to which springs 17, as shown in Figure 1, may be connected or through which bolts 26 with nuts 27 thereon may be extended to clamp the sections of the tube together.

40 The section 15 of each ring is provided with an overlapping tongue 28 that extends over an end 29 of the section 16 and the opposite end of the section 16 is provided with a tongue 30 that extends over an end 31 at the opposite side of the ring 15. The overlapping tongues are provided with bolt holes 32 and 33 and the ends 29 and 31 are provided with registering holes 34 and 35, respectively. By this means the sections of the rings are adapted 45 to be placed over the tubular sections of the parts 10 and 11 of the tube and with the sections of the rings in position, bolts, as indicated by the numeral 36 are placed through the openings in the overlapping tongues and ends of the rings for securing the rings in assembled relation 50 on the parts of the tube.

In the design illustrated in Figure 2 a neck 37, similar 55 to the neck 10 is secured in a cylindrical flange 38 of a bell shaped screen section 39 of a television picture tube with the bolts 26, which are mounted in rings 40 and 41, and these rings are positioned against collars 42 and 43 of the screen section and neck, respectively. A gasket 44 60 may also be placed between the sections and the adjoining end walls 45 and 46 may be ground to form lenses, as shown.

With the parts formed in this manner the electron gun 65 in the neck section 10 may readily be separated from the large or screen section 11 of a television tube whereby the electron gun section may be removed and replaced without replacing the entire tube. It will also be understood that the screen section 11, which is preferably sealed, may also be removed and replaced without replacing the electron gun section or neck 10.

70 It will be understood that other modifications, within the scope of the appended claims, may be made in the

design and arrangement of the parts without departing from the spirit of the invention.

What is claimed is:

1. A two piece television picture tube comprising an elongated cylindrical electron gun section providing a neck, a fluorescent layer in one end of the neck a bell shaped section, a photosensitive layer in an end of said bell-shaped section, the end of the bell-shaped section in which the photosensitive layer is positioned being mounted in abutting relation with the end of the neck in which the fluorescent layer is positioned, said bell-shaped section having a cylindrical portion with a cylindrical flange extended therefrom and said cylindrical flange positioned to receive an end of the neck, a collar extended around the cylindrical section of the bell shaped section, a similar collar extended around the neck and spaced from the end thereof, rings positioned against the collars and fastening elements extended between the rings.

2. In a television picture tube, the combination which comprises a screen section having a cylindrical portion thereon and said cylindrical portion having a cylindrical flange extended therefrom and an annular collar on the outer surface, an electron gun casing also having an annular collar on the outer surface adapted to nest in the cylindrical flange of the screen section with the annular collar spaced from the end of the flange, rings formed with connected semi-circular sections positioned around the cylindrical portion of the screen section and also

around the electron gun section, and fastening elements extended between the rings for retaining the parts of the tube in assembled relation.

3. In a plural type television picture tube, the combination which comprises a screen portion and an electron gun portion, said screen portion having a neck with an extended cylindrical flange and having a transverse section with a photosensitive layer on the inner surface, said electron gun portion having an end adapted to nest in the cylindrical flange extended from the neck of the screen portion and having a fluorescent layer on the inner surface of the end adapted to be positioned in the cylindrical flange of the screen portion whereby the fluorescent layer of the electron gun portion transmits light to the photosensitive layer of the screen portion, a gasket positioned between the end wall of the electron gun portion and end of the neck of the screen portion, and fastening elements for retaining the end of the electron gun portion in the cylindrical flange of the neck of the screen portion.
